United States Patent Office

Des. 220,468

Patented Apr. 20, 1971

220,468

BOTTLE

Jerome Gould, Los Angeles, Calif., assignor to Gem Incorporated, Byhalia, Miss.

Filed Apr. 17, 1970, Ser. No. 22,485

Term of patent 14 years

Int. Cl. D9—01

U.S. Cl. D9—47

FIG. 1 is a perspective view of a bottle showing my new design;

FIG. 2 is a front elevational view;

FIG. 3 is a side elevational view; and

FIG. 4 is a top plan view thereof.

I claim:

The ornamental design for a bottle, as shown.
